THERMOSTATIC WAX POT

Eugene J. Ray, Beverly, Mass., assignor to United Shoe Machinery Corporation, Paterson, N. J., a Corporation of New Jersey

Application April 19, 1929. Serial No. 356,475

7 Claims. (Cl. 219—44)

The present invention has relation to wax thread sewing machines such as are employed in the manufacture of shoes, and to the wax pots which are used in connection with such machines for the purpose of impregnating the thread with wax or similar substance previous to the incorporation of the thread in the seam formed by the sewing machine.

The invention has particular relation to the means employed in connection with such wax pots for heating the wax or other similar material for the purpose of rendering it fluid and capable of thoroughly permeating the thread as the latter passes through it on its way from the supply to the thread handling devices of the sewing machine.

The object of the present invention is to provide a novel and improved wax pot including heating means for the wax or other similar substance, said heating means having advantages over prior constructions in simplicity, cheapness, and compactness, in affording improved thermostatic control means for regulating automatically the electric heating units employed therein so that the wax shall always be kept at the proper temperature, and in provision for quick and easy removal of the heating units and the thermostatic control means in the event of injury thereto or need for adjustment thereof, without removal or disturbance of the parts other than those needing attention.

With this object in view, the invention consists in the novel and improved features, constructions, and combination of parts hereinafter described and particularly pointed out in the claims.

An illustrative embodiment of the preferred form of the invention is shown in the accompanying drawings in which Fig. 1 is a side elevation, partly in section and partly broken away, of a wax pot including the novel heating means; Fig. 2 is a front elevation of certain of the parts shown in Fig. 1, the wax receptacle being shown in section and certain of the other parts broken away; Fig. 3 is a plan view with the cover plate over the junction-block removed to disclose details of the connections as made through the use of said junction-block; Fig. 4 is a detail in vertical section showing the thermostatic circuit breaker in closed relation with respect to its contact points.

The wax receptacle 1 is supported from a bracket 3 which is adapted to be secured to the frame or column of the sewing machine in connection with which the thread waxing device is

to be used. Upon the bracket is pivotally supported by means of a stud 2 a cover 4 having a flaring lower portion 5 which overhangs and closes the open upper end of the wax receptacle 1. The latter is supported as is usual in this class of devices with its lip in proximity to the flaring portion 5 when in working relation and with capacity for movement downwardly away from the bracket 3 to give access to the parts enclosed within.

The means for heating the wax placed within the receptacle 1 comprises a pair of electric heating elements 6, 7, which are of elongated cylindrical shape, disposed within their respective chambers 8 and 9, formed within a housing 10 of heat-conducting metal which depends from the lower surface of the bracket 3, being attached thereto by means of screws 11 and with an asbestos gasket interposed to reduce the passage of heat from the housing. The housing is provided with wings 13, 14 extending laterally therefrom in parallel relation and perforated to permit free circulation of the molten wax, and joined at their bottom extremities by a web 15 upon which web between the said wings a porcelain thread guide 17 is secured by a yoke 16.

Through this guide the thread passes as it is drawn from the supply. This guide insures the thread being passed down below the level of the melted wax as it is drawn through the wax pot. In its upward travel, the thread is passed, after leaving the porcelain guide 17, through the slot in an auxiliary stripper 18 attached by screw 19 to the wing 13 to remove the major portion of the excess wax, and thence is caused to pass between an eccentrically-grooved stud 20 and a presser spring 21 bearing against said stud and mounted by means of a screw 22 upon the upper end of the housing 10, the spring acting as a wiper to complete the removal of excess wax adhering to the thread. The stud 20 extends horizontally from the end of an arm 23 formed integrally upon the upper end of the housing 10, and thus shares the heat generated in the housing. Thence the thread travels to the thread handling instrumentalities of the machine. The wings 13 and 14 upon each side of the path of the thread effectively prevent lumps of the cold wax which may be dropped into the wax receptacle to replenish the supply, from coming into contact with the thread.

The chambers 8 and 9 are formed as longitudinal passages extending through the housing from end to end thereof, so that the cylindrical heating units 6 and 7 may be easily removed.

The chambers 8 and 9 are formed as longitudinal passages extending through the housing from end to end thereof, so that the cylindrical heating units 6 and 7 may be easily removed.

from their respective chambers in the event of their swelling and binding therein, by the use of a tool employed to push them upward and introduced through the bottom of the housing 5 while the wax receptacle 1 is lowered. Each chamber is threaded at its lower extremity and fitted with a plug 25, 26 equipped with a gasket, and serving to close the lower end of the chamber and exclude melted wax therefrom.

10 The housing 10 includes within it a vertical passage 27 extending at its lower end into a chamber 28 lying below the level at which the wax is designed to be maintained and which has a portion 29 of circular area disposed in close 15 proximity to the chambers 8 and 9 holding the heating units, being separated therefrom by the thin wall 100. In this portion 29 of the chamber is located the thermostatic controlling means or circuit breaker for governing automatically the 20 flow of electric current employed to energize one of the two heating units. Such thermostatic control means comprise a bi-metallic heat responsive element 30 of the well-known concavo-convex type having when relatively cool a concavity facing in one direction and adapted upon 25 rise of its temperature to assume an opposite curvature or bulge, the transition in curvature taking place suddenly upon the attainment of a predetermined degree of temperature. This heat 30 responsive element is mounted upon a stud 31 passing through its center, being secured thereon by a nut 32, and is located in close proximity to the wall 100, which in turn is close to the surfaces of the heating units 6 and 7, to the full 35 heat from which it is exposed, with the interposition only of the thin wall 100 of the heat-conducting material of the housing, and with the least possible air-space separating it from the surface of such wall. The bi-metallic heat responsive member 30 is provided at three equidistant points about its edge-portion with discs 40 of current-conducting metal, insulated from the metal of the member 30, and adapted when the member is cool to make contact with, and bridge the gaps in, an interrupted segmental ring 31 affixed in insulated relation upon a circular plate 34 secured within a recess formed at the mouth of the portion 29 of the chamber 28. The plate 34 is held in place by means of screws 45 threaded into the material of the housing 40 with their heads overlapping marginal portions of the circular plate. The chamber 28 is accessible from the outside of the housing through a large opening permitting the installation and removal of the thermostatic circuit-breaker therethrough, without disturbing the connection between the bracket 3 and the housing 10, such opening being closed by a large plug 36 which is equipped with a gasket 37 and threaded into 50 said opening to keep wax from entering the housing and interfering with the action of the parts therein.

The leads carrying electric current to the 55 heating units and the thermostatic circuit-breaker, as well as the leads bringing such current from its source, are brought to a common junction-block located in an easily accessible position upon the bracket 3 and arranged to permit 60 easy and rapid disconnection of any one or more of the three elements included in the housing without disturbing the electrical connections to the remaining ones. This feature is of importance through expediting the repair or replacement of any one of the said three elements. 65 It is accomplished by providing within a box-

like compartment 39, or junction-box, as it may be termed, integrally formed in connection with the bracket 3, a junction-block 40 of insulating material, secured in place by a screw 41 passed through it and threaded into the bottom of said compartment 39, and having two deep grooves 42 extending across its width and a third groove 43 disposed between said grooves and extending partway across its width. The leads 44 bringing electric current to energize the heating units 80 from a suitable source are equipped with binding lugs which are engaged and held within the respective grooves 42 by means of binding posts or screws 45, 46 received in threaded holes in the insulating junction-block 40. The leads 47, 85 48 carrying the energizing current to the heating unit 7 which is of low heat-producing capacity are joined respectively to the ends of the leads 44 by means of the said two binding posts or screws 45, 46, said leads being brought up 90 through the chamber 9 in the housing and through an opening 49 coinciding therewith formed in the bottom of the compartment 39. With this arrangement the low power heating unit is in circuit and continuously acting so long 95 as the current is permitted to flow from the source through the line leads 44.

The leads 50 and 51 from the heating element 6, which has the greater heat producing capacity, are brought up through the upper portion of 100 the chamber 8 and through an opening 52 coinciding therewith in the bottom of the compartment 39, and are combined respectively with the binding post or screw 45 engaging one of the line leads 44 carrying the current from its 105 source, and with a binding post or screw 53 located within the groove 43 disposed midway across the insulating junction-block 40. To this binding post or screw 53 is also attached a lead 54 leading to one of a pair of binding posts 33 110 in connection with the interrupted ring 31 which is engaged by the discs 30 upon the heat responsive element 30. The lead 55 which extends upward from the other binding post 33 is combined with binding post or screw 46 and thus is connected with the source of electric power flowing through the conductors 44. A suitable opening 56 in the bottom of the compartment 39 communicates with the passage 27 through which the conductors 54 and 55 are 115 brought up to the junction-block 40.

With this arrangement of the parts, the low-power heating unit 7 is always in circuit with the line leads 44 and receives energizing current therefrom so long as the current is allowed 120 to flow through leads 44 from its source. The high-power heating unit 6 is connected in series with the thermostatic control means, or circuit-breaker, and these two combined elements are 125 connected in parallel with the low-power heating unit 7 across the line leads 44, so that current may pass simultaneously through the two heating units to melt the wax placed in the receptacle 1 around the central housing 10. When 130 the heat produced by the combined effect of the two units has raised the temperature of the heat-responsive member 30 to the predetermined degree, the member 30 assumes its reverse curvature with a snap. Up to this moment, the discs 30 have bridged the gaps in the interrupted ring 135 31 and formed portions of the circuit followed by the current in passing through the high-power heating unit 6, and have served to help carry the current from one of the binding posts 33 to the other thereof. Thus, the heat-re-

sponsive member 30, in reversing its curvature, has removed the discs 80 bodily from the circuit and interrupted the flow of current to heating unit 6. Thereafter the low-power unit 7 alone continues to supply heat, until the heat-responsive member has fallen a predetermined number of degrees in temperature, when it reverses its curvature and snaps back bringing discs 80 again into contact with the ring 81, and re-establishing the flow of energizing current through the high-power heating unit 6.

It has been found that the location of the concavo-convex type of heat-responsive member in close proximity to the heating units and exposed to the maximum heat given off therefrom while all the elements are included in a housing so that said member may follow closely the temperature changes of the heating units gives results which are superior, in the way of keeping the wax properly melted and of avoidance of burning the wax, to those results secured through separating such member from the heating units by insulating air-spaces, or by immersing it in the wax itself. This is because of the characteristics of this type of thermostatic member, which require the building-up of considerable stresses within the bi-metallic thickness before reversal of curvature can occur. Hence the circuit-opening temperature is a considerable number of degrees of heat above the circuit-closing temperature, and this change of temperature between maximum and minimum has no objectionable effect on the wax when the heating units and the thermostat are arranged as described within the housing 10, because through its spaced relation, the temperature of the wax is allowed to lag behind the high limit and remain above the low limit of the temperature variation of the metal of the thermostat.

Thus by means of the unique combination and arrangement of the parts in the invention, the advantages of the concavo-convex type of thermostat with its quick, wide, and energetic movement in breaking the circuit, which eliminates trembling and arcing and greatly prolongs the life of its contact-points, are secured in a thread-waxing device while avoiding the apparent drawbacks arising from its delayed action.

When it is desired to remove any one of the heating elements contained within the housing 10 for replacement or repair, the wax-receptacle 1 is lowered to give access to the housing 10, the appropriate plug 25, 26, 36 is removed, and a cover 60, secured to the rim of the junction-box 39 by means of screws 61 received in screw-holes 62 at its corners, is likewise removed to give access to the junction-block 40. Any one of the three elements combined within the housing 10 may be speedily disconnected from the binding posts 45, 46, 53, without disturbing the remaining elements, and may be then removed from the housing, the heating elements by being lifted up through the junction-box and the thermostat by being withdrawn through the opening closed by plug 36. The element is quickly replaced by a reversal of the procedure detailed.

Having thus described the invention what is claimed is:

1. A wax pot for wax thread sewing machines having, in combination, a receptacle for the wax, means for guiding the thread through the receptacle, an electrical heating unit within the receptacle, a housing to exclude the wax from contact with said heating unit, and a thermo-

static circuit breaker included within said housing and in close proximity to said heating unit to receive heat directly from the latter and control the electric current energizing the heating unit.

2. A wax pot for wax thread sewing machines having, in combination, a receptacle for the wax, means for guiding the thread through the receptacle, an electrical heating unit within the receptacle, a housing to exclude the wax from contact with said heating unit, a lateral aperture in said housing, a removable plug closing said aperture against admission of wax, and a thermostatic circuit breaker adapted to be received within said aperture into close proximity with the heating unit, and controlling the electric current energizing the latter.

3. Heating means for the wax pot of a wax thread sewing machine having, in combination, a housing, an insulated junction-block combined therewith and adapted to be connected with a source of electric current, an electric heating unit within said housing and having its terminals combined with said junction block, and a thermostat connected in series with said heating unit and having its terminals also combined with said junction block so that disconnection and removal of the heating unit may be effected without disturbing said thermostat.

4. Heating means for the wax pot of a wax thread sewing machine having, in combination, a housing, an insulated junction-block combined therewith having a plurality of binding posts of which two are adapted to be connected to a source of electric current, and a third independent therefrom, an electric heating unit removably positioned within said housing having its terminals respectively combined with one of the said two binding posts and with the third independent binding post, and a thermostat having its terminals respectively combined with the other of said two binding posts and with the third independent binding post, whereby the heating unit may be disconnected and removed without disturbing the thermostat and its connections.

5. A wax pot for wax thread sewing machines having, in combination, a receptacle for the wax, means for guiding the thread through the receptacle, an electrical heating unit within the receptacle, a housing to exclude the wax from contact with said heating unit, and a concavo-convex thermostatic circuit-breaker mounted in the housing in proximity to the heating unit to receive heat directly from the latter and control the electric current energizing the heating unit and arranged to follow closely in its temperature the rise of temperature of the heating element, and disposed in spaced relation with respect to the wax, to permit a relative divergence in temperature between the thermostat and the wax.

6. A wax pot for wax thread sewing machines having, in combination, a receptacle for the wax, means for guiding the thread through the receptacle, a housing extending into the wax in the receptacle, an electrical heating unit within the housing, and a concavo-convex thermostatic circuit-breaker in circuit with the electrical heating unit mounted in the housing in proximity to the heating unit to receive heat directly from the latter and control the electric current energizing the heating unit and separated from the wax by the housing, the arrangement of said circuit breaker, heating

unit and housing being such that the wax is heated through the housing by the heating unit and the temperature of the wax is allowed to lag behind the high limit and remain above the low limit of the temperature variation of the metal of the thermostatic circuit breaker.

7. A wax pot for wax thread sewing machines having, in combination, a receptacle for the wax, means for guiding the thread through the receptacle, an independently removable elec-

trical heating unit within the receptacle, a housing to exclude the wax from contact with said heating unit, and an independently removable thermostatic circuit breaker included within said housing and in close proximity to said heating unit to receive heat directly from the latter and control the electric current energizing the heating unit.
